CLAIM

An ornamental design for a portable canopy for camp or picnic table, as shown and described.

DESCRIPTION

FIG. 1 is a top plan view of a portable canopy for a camp or picnic table showing my new design;

FIG. 2 is a side elevation view thereof;

FIG. 3 is an enlarged cross-section taken on line 3—3 of FIG. 2 with portions fragmentarily shown and broken away for ease of illustration;

FIG. 4 is a side elevational view thereof; and

FIG. 5 is a bottom plan view thereof.

Fig. 1.
